INDICATOR FOR REVOLUTION COUNTERS

Arthur Rolfe Vinton, Little Britain, N. Y.

Application April 6, 1939, Serial No. 266,293

2 Claims. (CL. 116—114)

My invention relates to indicators for revolution counters.

Among the desirable objects of my invention is the provision of simple means for displaying a warning sign or reminder at the end of a pre-determined number of revolutions.

Other desirable attributes of my invention will hereinafter appear.

It is chiefly adapted for use in connection with automobile speedometers to remind the driver at the expiration of each 500 or 1000 miles that he should change oil and grease his car.

Broadly speaking, the invention comprises means for producing relative movement between a shield member and a sign member, so that in one relative position of such members a legend on the sign member is invisible and in another relative position it is visible.

One convenient form of the invention comprises an indicator mounted behind a fixed apertured shield, the sign on which the legend is placed being moved into and out of register with the aperture or window of the shield. The shield ordinarily consists of the face of the speedometer or other instrument casing.

In the preferred form of construction the sign is rotatably mounted and is provided with a spring for turning it from invisible into visible position as soon as a latch or catch is released by the speedometer or other form of revolution counter at the expiration of each revolution or part of a revolution of one of the wheels of the counter. After the latch has been tripped and the sign moved into visible position, the parts may be manually reset for operation at the end of the next succeeding revolution or part thereof.

Reference will now be had to the accompanying drawing, illustrating a practical embodiment of my invention, similar parts being designated by similar reference numbers, and in which:

Figure 1 is a front elevation of a speedometer with an indicator embodying the present invention mounted thereon;

Figure 2 is a top plan view of the indicator alone;

Figure 3 is a section on the line 3—3 of Figure 2, with the location of the parts in sign-displaying position indicated in dotted lines;

Figure 4 is a section on the line 4—4 of Figure 3;

Figure 5 is a section on the line 5—5 of Figure 2 with the parts in sign-displaying position;

Figure 6 is a front elevation of the indicator alone; and

Figure 7 is a detail view showing the re-setting key and parts cooperating therewith.

The practically workable exemplification of the indicator of my invention illustrated in the accompanying drawing will now be particularly described as to its construction and manner of operation.

The indicator is shown as applied to a speedometer of a standard type comprising a casing 10, speed indicating drum 11, and mileage indicator 12. Only such parts of the speedometer are shown as are necessary to illustrate the operation of my indicator.

The indicator is mounted in the lower part 15 of the speedometer casing and a window is provided in the face of the speedometer casing through which the legend on the sign is displayed when the mileage mechanism reaches the predetermined figure and operates the indicator.

Instead of using a movable screen between the window of the speedometer and a fixed sign, it is simpler to move the sign itself. This second mode of operation is that used in the form of construction illustrated in the drawing.

The indicator comprising a U-shaped frame formed of a back-plate 15 adapted to be secured to the base plate of the speedometer, and two forwardly extending arms 16. On this frame is mounted a sign on which is placed the desired legend. This sign is so mounted that it is capable of assuming one or other of two positions, in one position the legend being visible and in the other invisible through the window in the front of the speedometer casing.

One convenient mode of supporting the sign is to mount it on a shaft 17 journalled in the arms 16 of the frame. This shaft 17 has secured thereto an angle plate 20 bearing on one face the legend "Change oil grease." A strip steel spring 21 is provided for turning the shaft 17. For that purpose this spring is coiled around the shaft 17 and secured thereto by thrusting one end into a radial recess in the shaft, as shown in Figures 3 and 5. The other end of the spring 21 is formed with a U-shaped end slidably engaging a pin 22 on one of the arms 16. The spring is tensioned so that, when free to act, it turns the shaft and its attached plate from the position shown in Figure 3 to that shown in Figure 5.

Various means may be employed for releasably holding the shaft 17 in such angular position that the legend on the sign is invisible. As shown, such means comprises a shaft 18 journalled in the arms 16 of the frame and carrying an arm 24 terminating in a catch 25 adapted to

engage a shoulder on the shaft 17 and hold it against the pressure of the spring 21 in the position shown in Figure 3. The rear end of the arm 24 extends downwardly and carries a pin 26 which extends into one end of a coil compression spring 27. A similar pin 28 on the back-plate 15 extends into the other end of the coil spring 27. This spring, being under compression, tends to turn the shaft 18 so as to hold the catch 25 in engagement with the shoulder on the shaft 17.

The shaft 18 also carries another arm 30, the free outer end of which normally lies in the path of a pin 31 on one of the numeral wheels 32 of the mileage indicator. As shown, this wheel is the hundreds wheel, so that the pin 31 engages the arm 30 every 1000 miles. When the pin strikes the arm 30, the shaft 18 is turned against the pressure of the spring 27 so as to move the catch 25 out of engagement with the shoulder on the shaft 17 and thereby permit it to be rotated by its spring 21, as indicated in Figure 5.

After the catch has been tripped and the warning legend displayed and acted upon, it is necessary to re-set the indicator. Various means may be employed for this purpose. In the particular construction shown, the re-setting mechanism comprises two links 35 and 36 pivotally connected together at 37. The link 35 is also pivotally connected at 38 to a bracket 39 secured to the inner face of the angle plate 20.

The other link 36 is non-rotatably mounted on a shaft 40 journaled in lugs 41 and 42 extending downwardly and forwardly from the back-plate 15. When the shaft 17 is turned by its spring, the links 35 and 36 move from their full-line position of Figure 3 to their dotted line position. As in the dotted-line position, the links are in a straight line, they positively prevent further rotation of the shaft 17 and likewise prevent any possibility that jarring of the indicator will return the parts to their initial or full-line position. To re-set the indicator the shaft 40 has to be turned. While that might be accomplished by a knurled knob at the end of the shaft 40, a more satisfactory method is to use a flat key 45 having a slot 46 at its end for engagement with a pin 47 extending transversely across a cup 48 mounted on the end of the shaft 40, as shown in Figure 7.

It will thus be seen that my invention presents a device in which a sign carrying desired information will be exposed to view after a predetermined number of revolutions of a device operating therewith.

I do not limit myself to the size, shape, number or arrangement of parts as disclosed and described as these are given simply as a means for clearly describing the subject matter of my invention.

What I claim is:

1. An indicator for revolution counters of the gear-connected number-wheel type, comprising a shaft, a sign having a legend thereon mounted on said shaft, a spring adapted to rotate said shaft into a position in which the legend on said sign is visible, a latch pivotally mounted to turn about an axis parallel to said shaft and adapted to hold said shaft against the tension of said spring in an angular position in which the legend on the sign is invisible, a spring for yieldably holding the latch in operative connection with said shaft, means mounted on one of the wheels of the revolution counter for swinging said latch against the pressure of its spring to break said operative connection whereby the first-mentioned spring will rotate the shaft to bring the sign into legend-visible position after a predetermined number of revolutions, a second shaft parallel to the first shaft and a connection between the two shafts, whereby rotation of the second shaft turns the first shaft against the tension of its spring and re-sets the indicator.

2. An indicator for revolution counters, comprising a shaft, a sign having a legend thereon mounted on said shaft, means for exerting continuous pressure tending to rotate said shaft into a position in which the legend is visible, a retractile latch adapted to hold said shaft against the pressure of said means in an angular position in which the legend is invisible, latch-tripping means operated by the revolution counter whereby said first-mentioned means will rotate the shaft to bring the legend into visible position after a predetermined number of revolutions, and re-setting mechanism comprising two links pivotally connected together at their adjacent ends, the other end of one link being pivotally connected to a part carried by and extending laterally from said shaft, a second shaft rotatably mounted in fixed bearings, the other end of the other link being non-rotatably secured to said second shaft and means for turning said second shaft to cause the last-mentioned link through the intermediary of the first link to rotate the first shaft in a direction opposite to the direction in which it was rotated by said first-mentioned means.
